DESIGN FOR A COMBINED MOTOR ENCLOSURE AND SUPPORT FOR TRACTORS OR THE LIKE

John R. Morgan, Oak Park, Ill., assignor to Sears, Roebuck and Co., Chicago, Ill., a corporation of New York

Application July 14, 1937, Serial No. 70,414

Term of patent 14 years

To all whom it may concern:

Be it known that I, John R. Morgan, a citizen of the Republic of Guatemala, residing at Oak Park, in the county of Cook and State of Illinois, have invented a new, original, and ornamental Design for a Combined Motor Enclosure and Support for Tractors or the like, of which the following is a specification, reference being had to the accompanying drawing, forming a part thereof.

Fig. 1 is a front elevational view of a combined motor enclosure and support for tractor or the like embodying my new design.

Fig. 2 is a top plan view of the same.

Fig. 3 is a side elevational view thereof.

I claim:

The ornamental design for a combined motor enclosure and support for tractors or the like, as shown.

JOHN R. MORGAN.
